JOSEPH BETHENOD, OF PARIS, FRANCE, ASSIGNOR TO SOCIETE DES MOTEURS DUGELAY,
OF PARIS, FRANCE, A LIMITED COMPANY OF FRANCE

FUEL SUPPLY SYSTEM FOR INTERNAL COMBUSTION ENGINES OF VARIABLE LOAD FOR
USING HEAVY FUELS

Application filed August 29, 1928, Serial No. 302,803, and in Belgium September 27, 1927.

The usual spray carburetor as at present known in various forms, generally produces a sufficiently satisfactory fuel supply for internal combustion engines, provided that the fuel is very volatile.

The object of my invention is to provide a novel arrangement allowing the use of heavy fuels, even when operating under variable loads, on internal combustion engines of the ordinary type, that is without using the well-known expedients applied to engines of Diesel or semi-Diesel types.

A preferred embodiment of my invention is described in the following specification and shown in the accompanying drawing which shows the invention diagrammatically.

The intake manifold of the engine which is assumed to be of normal type, is supplied with air by means of an opening 4 which is controlled at will by a valve 3 of any familiar type. Situated at a convenient point on the manifold 2 which is beyond the said valve, in the sense of the flow of air, is the outlet of an auxiliary pipe 12 through which is delivered the explosive mixture of gases. These gases are delivered in a mixture having proper proportion of each for any load, by means of the following expedient:

The engine 1 drives synchronously a volumetric pump 9 of any type, such as plunger pump, bucket-wheel pump, or radial vane-wheel pump, which volumetric pump sucks per second a weight of air proportional to the weight of air flowing through the valve 3 during the same time, in consequence of the suction produced by the engine. The volumetric pump draws in a constant volume per stroke, that is, its capacity is proportional to its speed. Moreover, it will be easily seen that this proportion can be obtained at any load, by use of convenient arrangement and dimensions of the admission opening 4 of the intake manifold and of the admission opening 5 of the first auxiliary pump, this latter being moreover provided with a valve 6 mechanically connected with valve 3 by a rod or similar element 14. In this way, whatever is the opening of this latter valve 6, the desired proportional relation is obtained for any speed of the engine. The intake pipe 5

of the first auxiliary pump 9 leads to a spray carburetor 7 similar to those used with gasoline; the nozzle, or nozzles of this carburetor deliver, per unit of time, a weight of liquid fuel proportional to the weight of the air drawn in by the first auxiliary pump 9, that is to say proportional also to the weight of air flowing through the main valve 3. In principle, any familiar type of carburetor may be used, but preferably there should be used a carburetor of the type described as the "submerged nozzle" type. It is thus possible to obtain at the outlet of the pump a very rich mixture, of exactly correct proportions in weight at any load, with respect to the air directly drawn in by the engine through the opening controlled by the valve 3. This very rich mixture is delivered into an intermediate tank or reservoir 10 in communication with a second auxiliary pump 8, the dimensions of which are such as to produce a vacuum of appreciable value in said reservoir 10, that is, a pressure appreciably less than atmospheric pressure, in spite of the admission of said mixture. The mixture delivered into the reservoir 10 is vaporized because of the vacuum in the reservoir, and the gaseous mixture so produced is finally delivered into an auxiliary pipe 12 connecting the outlet of the second pump 8 to a convenient point on the intake manifold of the engine. The second auxiliary pump 8 discharges through the pipe 12 at a pressure which is ordinarily a little less than atmospheric pressure, and is approximately the same as or slightly greater than the pressure at a given time in the intake manifold, at the point where delivery pipe 12 terminates.

The engine then draws in a mixture of air and of combustible gases correctly proportioned at any load, and means can be provided in order to accelerate the mixing and secure a perfect homogeneity of said mixture. In order to be sure that all the combustible liquid delivered by the nozzle of the carburetor, is driven towards the first auxiliary pump, it is possible to use a carburetor of the vertical type, in which the direction of circulation of gases is directed from top to bottom, that is to say in a reversed sense.

with respect to the direction generally employed. Further it is possible also to keep the normal direction and to place under the carburetor a cup, in order to collect the un-delivered liquid, this latter being driven back to the first pump 9 by the use of any convenient device for this purpose, such as a small pump.

In any case, a supplementary nozzle device can be added to the outlet of the first pump in order to make easier the formation of vapors in the intermediate tank or reservoir; it is also possible to provide as additional means, cooling devices, or even catalyzers, as is well known in the art.

Further, it is intended that the admission of explosive mixtures in the cylinders of the engine can be secured by valves which are separate from the valves drawing in the air necessary for creating the explosive mixture.

The second auxiliary pump 8 which produces the incomplete vacuum which is necessary for the production of the gaseous mixture, can be of any desired type, rotary or otherwise, and can be driven either by the engine or by any other means. While I have shown in the drawing the second auxiliary pump 8 on the same shaft as the first auxiliary pump 9, it is to be understood that a geared connection of shafts may be employed to obtain proper speed at desired points.

The intake 4 has for its purpose to furnish to the motor almost all of the air necessary for combustion, while the intake 5 furnishes only a very small quantity of air, just what is necessary for picking up the liquid coming from the carburetor 7, which process of picking up yields a very rich mixture. It would not be desirable that all the air necessary for the combustion should enter through the intake 5, for the dimensions of pumps 8 and 9 would then be considerably increased, and further the passage of so great a quantity of air would be very detrimental for vaporization in the vacuum within the chamber 10. Chamber 10 receives only the liquid to be vaporized accompanied by a quantity of air which is as small as possible.

The purpose of volumetric pump 9 is to maintain for every position of control lever 15 the correct proportion between the pure air introduced at 4, and the gas or vapor delivered through pipe 12. That is, if volumetric pump 9 were omitted and it were attempted to control admission through orifice 5 by throttle 6 alone, it would not be possible to couple regulating valves 3 and 6 by link 14 and secure proper operation with automatic cooperative adjustment of the valves, and for each new position of regulating valve 3 it would be necessary to find manually by trial and error the correct position of the regulating valve 6 which would greatly increase the difficulty of operation of the motor.

To secure improved operation it may be found desirable to employ a reheating element 11 surrounding the reservoir 10, and another reheating element 13 surrounding the delivery pipe 12. Such reheating elements are well known in the art, and may be of any familiar type, such as water-filled or filled with hot gas. These may be jackets filled with water or hot gases. Such reheating at reduced pressure will materially facilitate vaporization.

The supply system here described makes it possible to use heavy fuels with an ordinary carburetor such as a spray carburetor which procedure would not otherwise be possible.

The arrangement of the reservoir 10 between the two pumps 8 and 9 in series, makes possible the adjustment of the mixture in the reservoir as a function of the load on the motor.

While I have described a preferred embodiment of my invention, I desire that it be understood that modifications may be made and that no limitations upon my invention are intended other than are proposed by the scope of the appended claims.

What I claim as new and desire to secure by Letters Patent of the United States is as follows:

1. In a system for supplying fuel and air for internal combustion engines using heavy fuels, in combination, a carburetor to which liquid fuel is delivered, a main intake manifold, an auxiliary intake, a first auxiliary volumetric pump driven synchronously by the engine, a reservoir, a second auxiliary pump, said auxiliary intake, carburetor, first auxiliary pump, reservoir, and second auxiliary pump, being arranged in the order stated with reference to the direction of flow of the gases, to constitute a means for delivering explosive mixtures to a suitable point in said intake manifold.

2. In a system for supplying fuel and air for internal combustion engines using heavy fuels, in combination, a carburetor to which liquid fuel is delivered, a main intake manifold, an auxiliary intake, a first auxiliary volumetric pump driven synchronously by the motor, a reservoir, a second auxiliary pump, said auxiliary intake, carburetor, first auxiliary pump, reservoir, second auxiliary pump, being arranged in the order stated with reference to the direction of flow of the gases to constitute a means for delivering explosive mixtures to a suitable point in said intake manifold, said second auxiliary pump producing a greater decrease in pressure in the reservoir than the increase in pressure in the reservoir due to the discharge from said auxiliary pump.

3. In a system for supplying fuel and air for internal combustion engines using heavy fuels, in combination, a carburetor to which

liquid fuel is delivered, a main intake manifold, an auxiliary intake, a first auxiliary volumetric pump driven synchronously by the motor, a reservoir, a second auxiliary pump, and means for maintaining a proportional relation between the quantity of air directly taken in through the main intake manifold, and the quantity of air taken in through the auxiliary intake, said auxiliary intake, carburetor, first auxiliary pump, reservoir, and second auxiliary pump, being arranged in the order stated with reference to the direction of flow of the gases, to constitute a means for delivering explosive mixture to a suitable point in said intake manifold.

4. In a system for supplying fuel and air for internal combustion engines using heavy fuels, in combination, a carburetor to which liquid fuel is delivered, a main intake manifold, an auxiliary intake, a first auxiliary volumetric pump driven synchronously by the motor, a reservoir, a second auxiliary pump, and means for maintaining a proportional relation between the quantity of air directly taken in through the main intake manifold and the quantity of air taken in through the auxiliary intake, said auxiliary intake, carburetor, first auxiliary pump, reservoir, and second auxiliary pump being arranged in the order stated with reference to the direction of flow of the gases, to constitute a means for delivering explosive mixtures to a suitable point in said intake manifold, and said second auxiliary pump producing a greater decrease in pressure in the reservoir than the increase in pressure in the reservoir due to the discharge from said first auxiliary pump.

5. In a system for supplying fuel and air for internal combustion motors using heavy fuels, in combination, a carburetor to which liquid fuel is delivered, a main intake manifold, an auxiliary intake, a first auxiliary volumetric pump driven synchronously by the motor, a reservoir, a second auxiliary pump, a valve for controlling the volume of air drawn in directly through the main intake, a valve for controlling the volume of air drawn in through said auxiliary intake, and a mechanical connection between the two said valves for maintaining a proportional relation between the areas of their admission openings, said auxiliary intake, carburetor, first auxiliary pump, reservoir, and second auxiliary pump being arranged in the order stated with reference to the direction of flow of the gases, to constitute a means for delivering explosive mixtures to a suitable point in said intake manifold.

6. In a system for supplying fuel and air for internal combustion motors using heavy fuels, in combination, a carburetor to which liquid fuel is delivered, a main intake manifold, an auxiliary intake, a first auxiliary volumetric pump driven synchronously by the motor, a reservoir, a second auxiliary pump

driven synchronously by the motor, said auxiliary intake, carburetor, first auxiliary pump, reservoir, and second auxiliary pump being arranged in the order stated with reference to the direction of flow of the gases, to constitute a means for delivering explosive mixtures to a suitable point in said intake manifold.

7. In a system for supplying fuel and air for internal combustion motors using heavy fuels, in combination, a carburetor to which liquid fuel is delivered, and in which the fuel circulates from top to bottom, a main intake manifold, an auxiliary intake, a first auxiliary volumetric pump driven synchronously by the motor, a reservoir, a second auxiliary pump, said auxiliary intake, carburetor, first auxiliary pump, reservoir, and second auxiliary pump, being arranged in the order stated with reference to the direction of flow of the gases, to constitute a means for delivering explosive mixtures to a suitable point in said intake manifold.

8. In a system for supplying fuel and air for internal combustion motors using heavy fuels, in combination, a carburetor to which liquid fuel is delivered, a main intake manifold, an auxiliary intake, a first auxiliary volumetric pump driven synchronously by the motor, a reservoir, a second auxiliary pump, a cup placed beneath the carburetor to collect the liquid which is not removed by said first auxiliary pump, means for drawing off the liquid existing between the cup and the said first auxiliary pump, and delivering it to the intake of said first auxiliary pump, said auxiliary intake, carburetor, first auxiliary pump, reservoir, and second auxiliary pump being arranged in the order stated with reference to the direction of flow of the gases, to constitute a means for delivering explosive mixtures to a suitable point in said intake manifold.

9. In a system for supplying fuel and air for internal combustion motors using heavy fuels, in combination, a carburetor to which liquid fuel is delivered, a main intake manifold, an auxiliary intake, a first auxiliary volumetric pump driven synchronously by the motor, a reservoir, a second auxiliary pump, means for spraying fuel between the said pump and the reservoir, said auxiliary intake, carburetor, first auxiliary pump, reservoir, and second auxiliary pump being arranged in the order stated with reference to the direction of flow of the gases, to constitute a means for delivering explosive mixtures to a suitable point in said intake manifold.

10. The method of supplying fuel to an internal combustion engine which consists in mixing in a carburetor liquid fuel with air taken in through an auxiliary intake, delivering the output of said carburetor to a volumetric pump which in turn delivers said mix-

ture to a reservoir in which said mixture is more thoroughly vaporized, delivering the output of said reservoir to a second pump, and finally delivering the output of said second pump to a convenient point on the main 5 intake manifold of said engine.

11. The method of supplying fuel to an internal combustion engine which consists in mixing in a carburetor liquid fuel with air taken in through an auxiliary intake, delivering the output of said carburetor to a volumetric pump which in turn delivers said mixture to a reservoir in which said mixture is more thoroughly vaporized, delivering the output of said reservoir to a second pump, 10 and finally delivering the output of said second pump to a convenient point on the main intake manifold of said engine and maintaining a proportional relation between the volume of air taken in directly by the main 15 intake manifold and the volume of air taken in by the said auxiliary intake.

12. The method of supplying fuel to an internal combustion engine which consists in mixing in a carburetor liquid fuel with air taken in through an auxiliary intake, delivering the output of said carburetor to a volumetric pump which in turn delivers said mixture to a reservoir in which said mixture is more thoroughly vaporized, delivering the 20 output of said reservoir to a second pump which produces a greater decrease in pressure in the reservoir than the increase in pressure in the reservoir due to the discharge from said first pump, and finally delivering the 25 output of said second pump to a convenient point in the main intake manifold of said engine.

13. In a system for supplying fuel and air for internal combustion motors using heavy 30 fuels, in combination, a carburetor to which liquid fuel is delivered, a main intake manifold, an auxiliary intake, a first auxiliary volumetric pump driven synchronously by the motor, a reservoir, a second auxiliary pump, 35 and means disposed around said reservoir for reheating the gaseous mixture, said auxiliary intake, carburetor, first auxiliary pump, reservoir, and second auxiliary pump being arranged in the order stated with reference 40 to the direction of flow of the gases, to constitute a means for delivering explosive mixtures to a suitable point in said intake manifold.

JOSEPH BETHENOD.
